UNITED STATES PATENT OFFICE.

HENRY W. BUHLER, OF BOSTON, MASSACHUSETTS.

COKE-OVEN.

1,341,257.

Specification of Letters Patent.

Patented May 25, 1920.

Application filed January 24, 1917. Serial No. 144,169.

To all whom it may concern:

Be it known that I, HENRY W. BUHLER, a citizen of the United States of America, residing at Boston, county of Suffolk, State 5 of Massachusetts, have invented certain new and useful Improvements in Coke-Ovens, of which the following is a specification.

My invention relates generally to heating apparatus, but, as at present advised, I believe it to have its most beneficial application in coke ovens of the down-draft flue type. The object of the invention is to render the heating action of such apparatus flexible of control and efficient in operation 15 and the flues and controlling parts easy of access for adjustment, cleaning, repair and observation. The best form of apparatus at present known to me embodying my invention is illustrated in the accompanying 20 drawings in which—

Figure 1 is a vertical, longitudinal section of a coke oven on two section planes slightly offset one from the other at the central line M—V, the left hand half of the section being 25 taken on planes indicated by dotted line A—B of Fig. 2, and the right hand half of the section being taken on dotted line C—D of Fig. 2, looking to the right in both cases.

Fig. 2 is a vertical cross section of the 30 oven (parts being broken away and omitted) on two section planes offset one from the other at the central line W—Z, the left hand half of the section being taken on a plane passing through dotted line E—F of Fig. 1, 35 and the right hand half of the section being taken on a plane passing through dotted line G—H of Fig. 1.

Fig. 3 is a detail horizontal section on line 3—3 of Fig. 2, and line L—M of Fig. 4, 40 and

Fig. 4 is a detail vertical section on line J—K of Fig. 3, parts being broken away in both figures.

Fig. 5 is a detail horizontal section on line 45 N—O of Fig. 4, parts being broken away.

Fig. 6 is a detail horizontal section on line T—U of Fig. 7, and

Fig. 7 is a detail vertical section on line 50 R—S of Fig. 6, parts being broken away, these figures illustrating the removable air nozzles on an enlarged scale.

Fig. 8 is a horizontal section on line X—Y of Fig. 1, parts being broken away and omitted.

Throughout the drawing like reference 55 characters indicate like parts. 1, 1, represent the retorts or coking chambers of a standard form of coke oven, in the walls 2, 2, of which are formed a series of vertical, down-draft combustion flues 3, 3. The bonding walls 19, 19, connecting oven walls 2, 2, form these flues 3, 3, and also the hot air flues 18, 18. Each combustion flue 3, discharges at its lower end into an individual waste gas passage 5, the connection to which 60 is controlled to a degree by an individual damper 4. The oven is of the duplex construction so far as its waste gas and recuperator connections are concerned, the lower transverse wall 15, dividing these portions 65 into two sections, which will now be described. A common collecting conduit 6, below the oven, communicates with all the passages 5, 5, on one side of wall 15, and through passageway 7, leads to a recuperator 70 of standard construction having horizontal waste gas chambers or flues 8, 9, connected at their inner ends. A pipe elbow 10, leads from the outer end of chamber 9, to chimney flue 12, the connection being controlled to a degree by a loose, sliding tile 11, serving as a general damper for the half 75 of the oven served by the left-hand recuperator. The recuperator structure is supported on cross beams 34, 34. The recuperator 80 for the right hand half of the oven is of the same construction but the plane of the section in this part of Fig. 1 is such as to show the air heating passages from inlet 13, lower chamber 14, through vertical tubes 32, 32, 85 90 sandwiched in layers between chambers 8, 8, and 9, 9, as shown in Fig. 2, into collecting chamber 16, and thence through channels 17, to vertical hot air flues 18, 18.

The hot air flues 18, and combustion flues 95 3, are in pairs in tandem, alternating with one another, and are connected at their upper ends to form heating pairs or couples as shown in Fig. 1. The above described construction is of standard type, except in so far 100 as the location of the recuperators under the oven in immediate connection with the flues thereof, the divided or duplex arrangement of waste gas connections, and the damper controls are concerned.

The features of my invention next to be described comprise the special means for connecting the air flues and combustion flues 105

in couples or pairs. As before stated these two sets of flues are connected at their upper ends as is customary in the down-draft flue type of oven, but these connections have 5 heretofore been inaccessible and permanent. According to my invention such connection is afforded through a vertical observation passageway 21, which extends through upper wall or roof 33, of the oven and is closed 10 at its upper ends by removable cover 22. The lower end of each passageway 21, abuts against and opens into the upper ends of a pair of flues 3 and 18, as shown in detail in Fig. 7. A removable air nozzle 20, is formed 15 of a block of refractory material which nearly fills the lower part of passageway 21, when in operative position. It wholly overlaps the discharge end of air flue 18, and partly overlaps the inlet end of a combustion 20 flue 3. This block has in its under portion a semicircular channel 30, which affords communication from air flue 18, to combustion flue 3. The stream of hot air received from flue 18, will thus be discharged downward 25 into combustion flue 3, and a long flame will be produced when fuel is also admitted to the upper end of flue 3. An alternative construction of block nozzle is shown at 20^a, in which channel 30^a is in the form of a quadrant of a circle, instead of a semi-circle, so 30 that the discharged current of air passes across the flue 3, instead of downward. Only this second form of nozzle is shown as 35 in use in Figs. 1, 2 and 4. This will produce a short flame. Still other forms of block nozzle may be used, each having a perforated lug 31, or 31^a, or other formation on its upper face which may be conveniently grasped by hook or tongs inserted through observation 40 passageway 21, for removal or replacement.

As shown the blocks 20 and 20^a, do not quite close the passageways 21, 21, and, if desired, the opening so left may be further enlarged by grooving the opposite wall as also 45 shown at 23. This affords ample room for inserting a rod into and through flue 3, to adjust individual damper 4, at the discharge port of the flue.

The next feature of my invention to be 50 described comprises the special fuel inlets employed. As usual these are located at the upper ends of the combustion flues 3, 3, but they are of an improved type comprising removable burner tubes 27, of refractory 55 material set in vertical passageways 29, in upper wall or roof 33, of the oven, terminating at their lower ends in removable burner nozzles 28, of still more refractory material. Preferably these nozzles are seated in ports 60 formed by the contracted lower ends of passageways 29, and do not extend to the bottom thereof, being thus hooded and partially protected from the heat in the combustion flues. 24, 24, are the gas pipes extending 65 over the oven top. They are offset some-

what from the line of the burner tube bore so that the burners can be easily withdrawn from their seats after unscrewing the elbow connections 26, 26. Valves 25, 25, control the supply of fuel.

70

In operation gas or other fluid fuel delivered through the burners to combustion flues 3, 3, combines with air from the air nozzles selected to produce the desired character of flame, and the gases of combustion 75 so formed pass off through the recuperator connections to the chimney flue. If inspection of any flue 3, through passage 21, and groove 23, after removal of cover 22, shows that proper combustion is not taking place 80 the conditions can be corrected by adjusting damper 4, or gas valve 25, or by changing air nozzle 20, or burner nozzle 28. If, after the relative rate or character of combustion in all the flues in one half of the oven has 85 been adjusted properly, it is desired to increase or decrease the combustion in that half as a whole; this is done by manipulating general damper 11, for that half. The hooding of the burner tip 28, partly protects it, 90 but it is partly destroyed after a period of use. A long hook inserted through tube 27, and tip 28, can then be used to withdraw the burner, after elbow 26, has been disconnected. A new burner tip can then be put 95 on and the burner returned to normal position and use.

The advantages of my invention comprise the efficiency of operation resulting from the immediate passage of the waste hot 100 gases of combustion from the flues into the recuperators located directly at the ends of the flues, and the immediate passage of the heated air from the recuperators directly into the hot air flues in the oven, the facility 105 of inspection of all flues, the ease of access thereto for cleaning, etc., and the flexibility of control by dampers of flue combustion individually or in bank, or by nozzle changes. With old forms of oven the character of the combustion going on can only be 110 judged by the general results obtained and a shut-down and general overhauling may be the only alternative to continued operation at reduced efficiency, but with my invention 115 the conditions in each flue or general locality can be instantly determined by inspection, the difficulty discovered and remedy applied without a moment's interruption of the general operation of the oven.

120

Another advantage resulting from the use of separate recuperators connected to separate sets of flues, one recuperator and its connected set of flues serving one end of the coking retort, and the other recuperator 125 and its connected set of flues serving the other end of the retort, is that the requirement for a difference between the extents of recuperative capacity at different ends of the retort can then be easily met. That is to say, 130

the retorts frequently flare in width slightly from one end of the other. Consequently there is a greater body of coal to be heated in one end than in the other. The recuperator under the wide end can then be made larger to heat the larger amount of air required at that end.

As the temperature to be produced in the combustion flues which heat the wider ends 10 of the retorts must be increased in at least as great a proportion as the retort width increases, and as the capacity of the recuperator must be increased at a greater ratio than the ratio of temperature increase in the 15 flues, it follows that the possible increase of width of recuperator resulting from the increase in width of the retort above it is not sufficient, but that a type of recuperator must be employed in which further increased 20 heating capacity may be given by increase of its vertical dimensions. Consequently the recuperators to handle such wider ends of the retorts should be of the construction here shown, *i. e.* such as have vertical air 25 passageways which can be lengthened to any desired extent, and the heating efficiency of the recuperator correspondingly increased thereby without necessarily increasing the width of the recuperator, which latter dimension is limited by the necessity for keeping the retorts above them as close together as possible for reasons of economy in construction and operation.

I wish it understood that various changes 5 can be made in the details of construction shown and described without departing from the substance of my invention so long as the general principles of operation and coaction of parts herein set forth are preserved.

Having described my invention, I claim:

1. A heating apparatus having in combination a series of vertical combustion flues with discharge outlets at the bottom, a series 5 of vertical air flues with inlets at the bottom alternating therewith, and a series of removable nozzles each of which connects the upper end of an air flue with the upper end of an adjacent combustion flue.
2. The combination, in a heating apparatus having a series of vertical combustion flues and a series of vertical air flues, the members of the two series alternating, being arranged in pairs in tandem and connected 5 at their upper ends to vertical observation passageways extending through the upper wall of the structure in line with the air flues so that each combustion flue and an adjacent air flue form a pair or heating couple, of removable blocks resting in said observation passageways on the tops of the air flues and channeled in their under portions to form, when in position, the means of communication between the flues of each pair.
3. The combination, in a heating appa-

ratus having a series of vertical combustion flues and a series of vertical air flues, the members of the two series alternating, being arranged in tandem and connected at their upper ends by vertical observation passageways extending through the upper wall of the structure in line with the air flues so that each combustion flue and an adjacent air flue form a pair or heating couple, of removable blocks resting in said observation 70 passageways on the tops of the air flues and channeled in their under portions to form, when in position, the means of communication between the flues of each pair, the parts being so formed as to also leave a 75 passage beside the block into the combustion flue.

4. The combination, in a heating apparatus having a series of vertical combustion flues and a series of vertical air flues, the 80 members of the two series alternating, being arranged in pairs in tandem and connected at their upper ends by vertical observation passageways extending through the upper wall of the structure in line with the air 85 flues so that each combustion flue and an adjacent air flue form a pair or heating couple, of removable blocks resting in said observation passageways on the tops of the air flues and channeled in their under portions to form, when in position, the means of communication between the flues of each pair, the parts being so formed as to also leave a 90 passage beside the block into the combustion flue, together with a removable 95 cover for the upper end of the observation passageway.

5. The combination, in a heating apparatus having a series of combustion flues and a series of air flues, of removable nozzles affording the means of communication from the air flues to the combustion flues and a series of removable gas nozzles discharging into the upper ends of the combustion flues.

6. A heating apparatus having vertical 105 combustion and air flues side by side in pairs, fuel inlets at the upper ends and waste gas outlets at the lower ends of the combustion flues, and observation passageways extending from the upper ends of 110 combustion and air flues to the top of the structure, in combination with dampers at the lower ends of the combustion flues and air nozzles located in the lower ends of the 115 observation passageways bridging the connection from air to combustion flues, the lower walls of the observation passageways being slightly grooved at one side to afford access from the said passageways by the air nozzles to the combustion flues and access to 120 the dampers.

7. A heating apparatus having vertical 125 combustion and air flues side by side in pairs, fuel inlets at the upper ends and waste gas outlets at the lower ends of the 130

4

combustion flues, and observation passageways extending from the upper ends of combustion and air flues to the top of the structure, in combination with dampers at the lower ends of the observation passageways bridging the connection from air to combustion flues, the lower walls of the observation passageways being slightly grooved at one side to afford access from the said passageways by the air nozzles to the combustion flues and access to the dampers, said air nozzles being formed of blocks of refractory material nearly filling the lower ends of the observation passageways, normally resting on and overlapping the mouths of each pair of flues and provided in their lower portions with passages ex-

tending from one abutting flue mouth to the other abutting flue mouth of each pair.

8. A heating apparatus having in combination a series of vertical combustion flues alternating with a series of vertical air flues, each member of one series being connected to a member of the other series, thereby forming a series of pairs each composed of a combustion flue and an air flue, connections between the upper ends of the members of each pair, and a recuperator located directly under the apparatus, together with direct connections from its air passages to the lower ends of the air flues and from its heating passages to the lower ends of the combustion flues.

HENRY W. BUHLER.
